UNITED STATES PATENT OFFICE

2,640,673

CAN OPENER BRACKET

Achille G. Bureau, Forest Hills, N. Y., assignor to
 Joseph A. Cahil, doing business as Cahil Manufacturing Company, New York, N. Y.

Application April 19, 1950, Serial No. 156,741

3 Claims. (Cl. 248—289)

1

The present invention relates to can openers and embodies, more specifically, an improved form of bracket or mounting by means of which can openers of conventional form may be mounted upon a wall and conveniently moved from, and be retained in, either an operative or one or more inoperative positions.

It has long been common practice to mount can openers on walls and by means of brackets whereby the can opener may be swung from a position generally parallel to the wall to one generally at right angles, and in which the operation of the opening of the can may be conveniently accomplished. A difficulty with the foregoing previously existing devices has long existed because of the fact that when not in use, the can opener may accidentally project out and away from the wall, and thus serve as an obstacle. It is an object of the present invention to provide a can opener mounting by means of which the can opener may be effectively maintained either in an operative position or in one or more normally inoperative positions in which the can opener is mounted closely adjacent the wall, and so that it does not form an obstacle.

In order to accomplish the invention, a bracket is provided having mechanism by means of which the can opener supporting arm may be locked effectively in either of a plurality of positions and wherein the lock may be readily released.

The invention will be understood more fully from the accompanying drawings, wherein

Figure 1 is a view in front elevation showing a can opener and mounting bracket constructed in accordance with the present invention;

Figure 2 is a plan view of the structure shown in Figure 1;

Figure 3 is a partial view in cross-section, taken on the line 3—3 of Figure 4, and looking in the direction of the arrows;

Figure 4 is a view in section, taken on the line 4—4 of Figure 2, and looking in the direction of the arrows;

Figure 5 is a view in section, taken on the line 5—5 of Figure 1, and looking in the direction of the arrows; and

Figure 6 is a view similar to Figure 5 showing the latch mechanism moved to an inoperative position such that the can opener arm may be moved into a desired position.

With reference to the above drawings, a can opener mounting arm is illustrated at 10 and contains a conventional form of can opener mechanism adapted to be operated by a manually operated handle 11 that is journaled in the

arm 10. Inasmuch as the details of the can opening mechanism forms no part of the invention, it will not be described in greater detail here.

In order that the arm 10 may be moved from an inoperative position (such as is illustrated in Figure 2) to an operative position in which the arm 10 lies in a plane at right angles to the plane in which such arm lies in Figure 2, a bracket 12 is provided and is adapted to be mounted upon a wall 13. The bracket is formed with upper and lower flanges 14 and 15, respectively, between which flanges a sleeve 16, formed on the arm 10, is adapted to be received. The sleeve 16 is formed, as illustrated in Figure 3, by the adjacent end portions 17 of a cover 18 of the arm 10, and also by the end 19 of a central supporting web 20 of the arm 10.

Within the end 19, a hollow hinge sleeve 21 is provided, the hinge sleeve being secured to the end 19 by means of screws 22 and being sufficiently long to extend through the flanges 14 and 15 (Figures 4, 5, and 6). The bottom of the sleeve 21 is formed with four notches 23 that are spaced ninety degrees apart, and the bracket 12 and the lower flange 15 are formed with a slot 24.

Within the sleeve 21 a manually depressible plunger 25 is provided, the plunger being urged upwardly by means of a coil spring 26 that is seated upon a shoulder 27 carried by the sleeve 21. A stem 28, carried by the plunger 25, extends downwardly through the sleeve and, at its lower extremity, is formed with a latch plate 29 having a latching shoulder 30 that is adapted to engage the notches 23 and a flange 31 that is adapted to engage the slot 24.

From the foregoing description it will be seen that the arm 10 may be secured in either of three positions (two of which are spaced one hundred eighty degrees apart and lie parallel to the wall 13, and the third position of which lies at ninety degrees to the plane of the wall 13). The mechanism by means of which the arm may be latched in either of these positions comprises the manually depressible plunger and the plate 29 actuated thereby, and the operation thereof will be apparent from an inspection of Figures 5 and 6. When the plunger 25 is depressed, the latching shoulder 30 is disengaged from the notches 23, and the can opener bracket 10 may be swung into any desired position. When such swinging motion has been initiated, the plunger 25 may be released, and the shoulder 30 will ride on the bottom of the sleeve 20 until the next notch 23 is reached, at which time the shoulder

will be snapped into the notch to latch the arm in the appropriate position.

While the invention has been described with specific reference to the accompanying drawings, it is not to be limited save as defined in the appended claims.

I claim:

1. Can opener mounting mechanism, comprising a mounting bracket, a can opener arm, a sleeve on the arm journaled in the bracket, a latch mounted in the sleeve and engaging the bracket and sleeve to secure the arm in a plurality of positions, and a spring housed within said sleeve to urge the latch into a latching position.

2. Can opener mounting mechanism, comprising a mounting bracket, a can opener arm, a sleeve on the arm journaled in the bracket, a plurality of notches in the sleeve, a latch mounted in the sleeve and having a shoulder adapted to engage the notches selectively, a spring to urge 20 the latch into the notches, and means to prevent

rotation of the latch with respect to the bracket.

3. Can opener mounting mechanism, comprising a mounting bracket having upper and lower flanges, a can opener arm, a sleeve fixed to said arm journaled in the flanges of said bracket and having a plurality of notches formed in the lower end of said sleeve, a latch plate mounted in said sleeve and having a shoulder adapted to engage the notches selectively, a spring housed within 10 said sleeve to urge said latch plate up into the notches, and means to prevent rotation of said latch plate with respect to said bracket.
